UNITED STATES PATENT OFFICE.

JAMES R. WHELEN, OF DENVER, COLORADO.

DESIGN FOR A MEAT-TENDERER PLATE.

SPECIFICATION forming part of Design No. 33,703, dated December 11, 1900.

Application filed November 7, 1900. Serial No. 35,773. Term of patent 14 years.

To all whom it may concern:

Be it known that I, JAMES R. WHELEN, a citizen of the United States, residing at Denver, in the county of Arapahoe and State of Colorado, have invented and produced a new and useful Design for Meat-Tenderer Plates, of which the following is a specification.

My invention relates to new and original designs for meat-tenderer plates.

10 In the accompanying drawings, Figure 1 is a plan view of a meat-tenderer plate, showing my new design. Fig. 2 is a side view thereof.

15 As shown in said drawings, my design consists of a rectangular plate, projecting from one surface of which is a series of studs, said studs being frusto-pyramidal in shape and arranged at equal distances apart in rows across the plate. Upon reference to Fig. 1 20 it will be seen that the studs of each alternate row are located in the spaces centrally between the studs of the next contiguous

row. Projecting outward from one edge of the plate are two perforated pintle-bearings, and upon the surface of the plate opposite 25 the studs a loop is formed.

The essential feature of my design is the rectangular plate having a series of frusto-pyramidal studs thereon, said studs being arranged in parallel rows, with the studs on 30 one row opposite the intervals in the two adjacent rows.

Having thus fully described my invention, what I claim is—

35 The design for a meat-tenderer plate, as shown and described.

In testimony whereof I have hereunto set my hand in presence of two subscribing witnesses.

JAMES R. WHELEN.
